UNITED STATES PATENT OFFICE.

CHARLES W. COLVIN, OF WILKES-BARRÉ, PENNSYLVANIA.

MINING-MACHINE.

SPECIFICATION forming part of Letters Patent No. 282,274, dated July 31, 1883.

Application filed February 1, 1883. (No model.)

To all whom it may concern:

Be it known that I, CHARLES W. COLVIN, a citizen of the United States, and a resident of Wilkes-Barré, Luzerne county, Pennsylvania, have invented certain Improvements in Mining-Machines, of which the following is a specification.

The main feature of my invention relates to certain improvements in the coal-drilling machine for which Letters Patent of the United States No. 223,590, dated January 13, 1880, were granted to J. R. Howells; and the object of my invention is to so construct the drill that the bit will be fed forward automatically only in proportion to the degree of hardness of the coal being cut. A further object of my invention is to so construct the feed-wheel that it will adapt itself to irregularities in the twist of the drill itself. These objects I attain as more fully described hereinafter.

In the accompanying drawings, Figure 1 is a vertical section of a drill embodying my invention; Fig. 2, a plan view, partly in section; and Fig. 3, a detached sectional perspective view of a modification, and illustrating a form of screw-nut I propose to use.

Referring to Fig. 1, A represents a suitable frame or standard for supporting the drill, similar to the stock illustrated in the above-cited Letters Patent. The standard is provided with toothed jaws, one of which is a continuation of the standard, and the other, B', hinged thereto. The standard and the arm b of the movable jaw B' are provided with a bolt, b', and nut b'', whereby the jaws may be expanded after insertion into a suitable opening in the breast of coal to be drilled, so as to firmly hold the standard and its parts in position.

On the standard A is mounted a frame, M, having bearings or collars E E', through which freely passes the drill G, the latter being preferably made in two parts joined by a socket, g, with their twists reversed, as shown in Fig. 1.

The bevel or feed wheel F, through which the drill passes, and which gears into the

bevel-pinion n on the transverse shaft N, has threads adapted to the twist of the drill. This feed-wheel F is in frictional contact with the bearing or collar E, so that when the crank-handle H is applied to the end of the shaft N, as shown in Fig. 2, a rotation of the handle to the right will cause the wheel F to rotate, and its threads acting on the twist of the drill will advance the latter in the direction of the arrow. When an increased resistance is offered to the advance of the drill, the latter will simply rotate with and at the same speed as the wheel; but as the threads in the hub of the wheel continually tend to push the drill forward the latter will advance just as rapidly as the material being cut will allow.

Instead of having the hub of the wheel F bear simply against the face of the collar E, an annular recess may be formed in the end of the collar, as shown in Fig. 3, for the reception of the hub of the wheel F, to increase the frictional surface between the two, only sufficient of the hub F being indicated in this figure to illustrate the modification.

As the twists of the drills G are not always uniform, I prefer to swivel or pivot the threads f f' in the feed-wheel F, as shown in Fig. 3, so that these threads will always adapt themselves to the twist of the drill.

I claim as my invention—

1. The combination of the frame of a mining-drill having bearings or collars for the free passage of the twist-drill with a driving-shaft and bevel-pinion, and a loose bevel-wheel gearing into the said pinion and having threads adapted to the twist of the drill, substantially as set forth.

2. The combination of a rotary drill with a feed-wheel having swiveled threads, as and for the purpose described.

In testimony whereof I have signed my name to this specification in the presence of two subscribing witnesses.

C. W. COLVIN.
